Patented Nov. 6, 1917.

UNITED STATES PATENT OFFICE.

BENJAMIN C. SMITH, OF BAYONNE, NEW JERSEY, ASSIGNOR TO STANDARD MOTOR CONSTRUCTION COMPANY, OF JERSEY CITY, NEW JERSEY, A CORPORATION OF NEW JERSEY.

INTERNAL-COMBUSTION ENGINE.

1,245,520.

Specification of Letters Patent.

Patented Nov. 6, 1917.

Application filed January 17, 1917. Serial No. 142,791.

To all whom it may concern:

Be it known that I, BENJAMIN C. SMITH, a citizen of the United States of America, residing at Bayonne, Hudson county, State of New Jersey, have invented a new and useful Internal-Combustion Engine, of which the following is a specification.

My invention relates to a fluid controlling means particularly useful for internal combustion engines. The invention may be applied to an engine of that type set forth in my copending application, Serial No. 137,117, filed Dec. 15th, 1916, wherein I have disclosed only manually operable means for effecting the control of the gas and air used in producing the combustible mixture. In the present case this control is effected automatically.

Whereas my present improvement is of particular utility when used in connection with such an engine as disclosed in my aforesaid application, its usefulness is not limited thereto but may be extended to other apparatus.

25 In the accompanying drawings:

The figure is a side elevation of an engine partly in section showing my apparatus as applied thereto.

1 represents a cylinder; 2 a piston; 3 an exhaust valve; 11 a gas fuel feed pipe leading from a generator 12 to a gas intake valve 9 which opens into the cylinder 1 at the proper time. 7 is an air intake pipe which leads to a valve 5 located in the cylinder 1, and which opens to admit air into the cylinder at the proper time. The valves 5—9 may be of any suitable type, the same being designed to open on the so-called suction stroke of the engine. 8 conventionally represents

40 a valve in the air supply pipe 7. 21 represents a cylinder having therein a piston 22, 23 is a duct or pipe connecting the interior of the fuel feed pipe 11, beyond the valve 18, with one end of the cylinder 21. 24 is 45 a duct or pipe connecting the air inlet pipe 7, beyond the valve 8, with the other end of the cylinder 21. The piston 22 is suitably connected with the valve 18 as through the medium of a rod 25 and an arm 26. The

50 valve 8 is a throttle and this may be operated in any well known way, that is to say, manually, or by any suitable form of governor, or a combination of either, all of which are too well known to require illustration but, for the purposes of this case, I

have elected to show an arm 27 which is manually movable over a notched segment 28 to different operative positions. 19 conventionally illustrates a valve by which I may regulate the density of the fuel-gas formed by the generator 12. Assuming a gas of the desired richness is being fed to the fuel pipe 11 ready to be introduced into the cylinder 1, and assuming the engine is running on the suction stroke the valves 5—9 will open simultaneously admitting fuel-gas and air which become mixed within the cylinder in the proper proportions to give the proper explosive mixture. To slow down the engine the throttle 8 is moved so as to restrict the passage through the pipe 7. This will result in reducing the volume of air admitted. Inasmuch as it is essential that the volume of gas should be proportionately reduced, it will be seen that the governing means will operate to that end as follows: Inasmuch as the right hand end of the cylinder 21 is connected with the air passage between the throttle valve 8 and the cylinder 1, it follows that the resulting rarefaction of air in the cylinder will be felt at once in the cylinder 21 at the right of the piston 22. This will result in drawing the piston 22 to the right and thereby closing down the valve 18 in the fuel pipe thus producing a rarefaction beyond said valve which will be felt on the left hand end of the cylinder 21 until there is a balance of pressures on both sides of the piston 22. When said condition obtains the piston 22 will stop moving and the valve 18 will occupy the proper position relatively to the set position of the throttle valve 8, whatever that position may be, to give the desired mixture.

I may also connect this automatic controlling means with the fuel controlling valve 19 so that more or less fuel will be automatically controlled from the automatic regulator simultaneously with the control of the gas. I have conventionally illustrated such a connection, the same comprising a lever 30 pivoted at 31 and connected with a suitable pin and slot connection with the upper end of the valve 19. The lever 30 is likewise connected by a rod 32 with a short crank 33 on the end of the arm 26 so that when the arm 26 moves to open the valve 18 it will simultaneously open the fuel valve 19. I have not attempted to illustrate herein accurate proportions, but rather

have merely shown conventionally an arrangement by which the aforesaid operation may be effected. For the purposes of further regulation, I may provide a bar 34 connected to the end of the pivot for the valve 18. This bar may have slidably mounted thereon two weights 36-36^a, one weight being mounted on each side of the pivot. By adjusting these weights on the rod 34 I 10 may balance the valve 18 as required, or as desired. For example, as shown in the drawings, the weight 36 is farther from the pivot for the valve 18 than is the weight 36^a, hence the normal tendency of the valve 15 will be to move in an opening direction, this tendency being counteracted by the degree of vacuum in the right hand end of the cylinder 21. When this degree of vacuum decreases, the relatively increased vacuum 20 in the pipe 11 beyond the valve 18 plus the weight 36 will tend to open valve 18.

What I claim is:

1. In an internal combustion engine, a cylinder, a piston therein, a fuel admission port opening into the cylinder and a valve therefor, an air admission port opening into the cylinder and a valve therefor, a conduit for supplying a relatively rich combustible gas to the valved fuel admission port, a conduit for supplying air to the valved air admission port, a valve in the fuel supply conduit for controlling the supply of fuel, a valve in the air supply conduit for controlling the supply of air, a control cylinder in communication at one end with the fuel supply conduit at a point between the fuel control valve and fuel admission valve 25

and in communication at its opposite end with the air supply conduit at a point between the air control valve and the air admission valve, a piston in said cylinder and subjected at its opposite sides to the pressure in the fuel and air supply conduits, means for operating one of the control valves and operating connections from the piston to the other one of the control valves. 40 45

2. In an internal combustion engine, a cylinder, a piston therein, a fuel admission port opening into the cylinder and a valve therefor, an air admission port opening into the cylinder and a valve therefor, a conduit supplying a relatively rich combustible gas to the valved fuel admission port, a conduit for supplying air to the valved air admission port, a valve in the fuel supply conduit for controlling the supply of fuel, a valve in the air supply conduit for controlling the supply of air, a control cylinder in communication at one end with the fuel supply conduit at a point between the fuel control valve and fuel admission valve 50 55

and in communication at its opposite end with the air supply conduit at a point between the air control valve and the air admission valve, a piston in said cylinder and subjected at its opposite sides to the pressure in the fuel and air supply conduits, means for operating one of the control valves, operating connections from the piston to the other one of the control valves, and a valve for regulating the density of the fuel also operated by the piston in the control cylinder. 60 65 70

BENJ. C. SMITH.
